UNITED STATES PATENT OFFICE.

HERMANN KARL EMIL LÜCKE, OF LÜBECK, GERMANY.

TAXIMETER.

1,392,895.

Specification of Letters Patent.

Patented Oct. 4, 1921.

Application filed February 12, 1921. Serial No. 444,532.

To all whom it may concern:

Be it known that I, HERMANN KARL EMIL LÜCKE, citizen of Germany, residing at 32 Sadowastrasse, Lübeck, Germany, have invented certain new and useful Improvements in Taximeters (for which I have filed an application in Germany, May 17, 1919), of which the following is a specification, reference being had therein to the accompanying drawing.

The subject-matter of the present invention is a taximeter for public vehicles which is switched in through the loading of spring seats. The innovation consists in that upon one or more seats being occupied a rope drum is turned in a measure corresponding to the number of seats loaded, through the agency of a Bowden type of a rope pulley drive of the well-known kind, which drum, upon the one hand, sets an indicator disk indicating the number of passengers, while, upon the other hand, it serves to regulate through the intermediary of a slide rod the transmission between the shaft driven by the car and the fare indicator as well as the fare adding device.

Upon the passenger or passengers sitting down, the clock is set automatically in the well-known manner to the rate or tarif corresponding to the number of passengers in the car. Upon starting, the clock is automatically engaged, the opening or window of the fare indicator is freed, the fare indicator, the integrating fare recorder as well as the two mileage recorders (of which one is for trips with passengers and the other for recording the total mileage covered) are caused to be actuated, and the time clock is coupled with the fare indicator and the integrating fare recorder. At stops or interruptions of the trip the said clock adds the amount for waiting time at the corresponding tarif.

Upon termination of the trip, and after the passenger has paid, no control on the driver's part is necessary any longer save for the counting or recording of the total number of miles covered by the mileage recorder which is permanently coupled with the car.

To protect himself from personal damages, seeing that after the passenger has left the car the clock would automatically continue recording, the driver must after

completed "occupied" trip at once set a special organ connected with the clock whereby the trip counter is advanced one number, the fare indicator is returned to the initial tarif, the clock is disengaged from the fare indicator and the fare recorder, while the opening or window previously uncovering the fare indicator is shut. On "idle" runs the fare indicators, fare recorders as well as the mileage recorder for trips with passenger remain disengaged, and the opening to the fare indicator is closed.

The clock automatically changes the indicator to day and night tarif, and it further allows of adjustment to certain increased or lower tarifs.

The slide for closing the meter openings is so arranged that, when uncovering the fare indicator window, it closes the openings of the trip recorder, the integrating fare recorders as well as of the two mileage recorders.

By means of an interchangeable tooth wheel the tarifs can be reduced by one half or be increased to the double amount such that the clock can be adapted to any desired tarif.

The drawing herewith illustrates the idea underlying the invention by way of example, of which—

Figure 1 is a diagrammatic view of the mechanism, looked at from in front in a plane.

Fig. 2 is a side view and assembly of the mechanism, partly in section.

Fig. 3 the drive from the clock and the mechanism for the changing over and indication of the day and night tarif.

Fig. 4 shows the mechanism for returning the counter wheels of the fare indicator to the initial tarif.

Fig. 5 illustrates the mechanism for raising the slide in front of the fare indicator opening and the disengaging of the clock with fare indicator and fare recorder.

Fig. 6 is a plan view of Fig. 5.

Fig. 7 illustrates the ratios of gearing of the replaceable or interchangeable tooth wheel 16 by means of which wheel the taximeter can be made to record on basis of any desired tarif per mile.

Fig. 8 shows the spring seat in section and plan.

Fig. 9 is a view of the drive of the total-

mileage recorder and the coupling of the mileage recorder running on trips with passenger.

Fig. 10 shows the taximeter from the outside, and

Fig. 11 shows the recesses in the slide for the indicator openings.

The drive of the clock is effected in the heretofore customary manner through a flexible shaft, the latter being coupled with one of the wheels of the car. The torque is transmitted to the shaft 2 through bevel wheels 1 (Fig. 1). On the said shaft, and rigidly fitted thereon, are transmission wheels 3 corresponding to the different rates or tarifs. In engagement with said transmission wheels 3 are transmission wheels 6 which are loosely fitted upon shaft 4 and only fixed by the aid of key 5. Rigidly mounted upon shaft 4 are transmission wheels 7 for the day and night tarif, and they mesh with transmission wheels 10 likewise loosely fitted upon shaft 8 and only coupled fast by key 9 subject to the control of the time clock.

Loosely arranged on shaft 8 is a tooth wheel 11 which, on the one hand, is driven by pawl 12 fixedly mounted upon shaft 8, and on the other hand, by pawl 15 connected through coupling 13 with tooth wheel 14 driven from the clock. Engaged with tooth wheel 11 through the intermediary of interchangeable tooth wheel 16 is tooth wheel 18 of the fare indicator, wheel 18 being loosely fitted upon shaft 17. Fixedly connected with tooth wheel 18 is toothed sector 19 which at each revolution advances tooth wheel 20 by two notches. Tooth wheel 20 is in mesh with counter roller or wheel 21 and pushes the latter one number ahead. Upon the right-hand side of the counter wheels is a solid or full toothed rim, while upon the left side there are but two teeth. Upon each complete revolution of the counter wheels, the counter wheels adjoining on the left-hand side are advanced one number through toothed wheels 20.

In engagement with tooth wheel 22 which is likewise rigidly united with tooth wheel 18, is a tooth wheel 24 corresponding to the integrating recorder mounted fixedly upon shaft 23.

The wheel of the units, 25, is fixedly connected with shaft 23 and thus pushes upon one revolution the wheels of the pens 26, ahead one number, and so on.

The drive from the time clock to the fare indicator and the fare recorder is accomplished from shaft 27 (see Fig. 3) of the seconds wheel which is connected with vertical shaft or spindle 29 through bevel wheels 28. At the bottom end of spindle 29 is another pair of bevel wheels, 30, which serves to impart motion to shaft 31. On the latter is spur wheel 32 (Fig. 1) which is in

engagement with tooth wheel 14 loosely mounted on shaft 8 and with tooth wheel 11 through coupling 13 previously referred to and pawl 15.

The pawls 12 and 15 upon their respective sides serve the object that, when tooth wheel 11 is being driven by pawl 12 fixedly mounted upon shaft 8, pawl 15 being in connection with the clock is caused to lag whereas, as soon as the car comes to a stop, 75 and pawl 12 comes to rest, pawl 15 keeps tooth wheel 11 in rotation. In this manner the price for the waiting time is being indicated.

The drive of the mileage recorders is effected through the intermediary of bevel wheels 34 being at a gear-ratio of 2:1 and rigidly mounted on shaft 2 (see Fig. 9) and shaft 33. The total-mileage recorder connected with shaft 36 is actuated through 85 worm 35 and the worm wheel 37 fixedly mounted upon shaft 36. On the latter are further loosely arranged and solely rigidly connected by coupling 38, the counter rollers or wheels 39 of the mileage recorder running on "occupied" trips.

The changing from day tarif to night tarif is accomplished by two cams 40 (Fig. 3) which are in connection with hour wheel 41. Levers 43 sliding or wiping over cams 40, at a pre-arranged time, slip off from the outer path, and, by action of the tension of spring 44, push wedge 9 (Fig. 1) through the agency of wedge bolt 45, alternately into transmission wheels 10 of the day and night 100 tarif. By simple shifting or change of teeth of gear wheels 42 (Fig. 3) any desired time for the change can be attained.

At the flange of wedge bolt 45 (Fig. 3) engages also the control of the indicator 105 for day and night tarif. By means of angle lever 47 engaging at the flange 45 pull rod 48 is pushed alternately upward and downward. The same moves toothed sector 49 which meshes with toothed wheel 50 (Fig. 110 2) with which the indicator segment 51 bearing the inscription "day tarif," and "night tarif," is fixedly connected.

The disengagement of the taximeter clock occurs by turning wing screw 52 one-third 115 revolution (see Figs. 1 and 10). This causes tooth wheel 53, entrained by pawl 54 (see also Fig. 4) to be rotated. Tooth wheel 53 meshes with tooth wheel 55 fixedly disposed upon shaft 17 (see Fig. 1), the said two 120 tooth wheels being at a gear ration of 1:3. On shaft 17 sit furthermore fixedly arranged thereon levers 56 (see also Fig. 4) which are inserted between the counter rollers and each of which carries a pawl 57. In the said 125 counter rollers, below each number, are threaded holes for receiving a stop (pin) 58 for pawls 57. No matter what position the counter rollers may occupy prior to disengagement, the result is that at a complete 130

revolution of shaft 17, stops 58 (of which there is but one on each counter wheel) are made to assume a definite position. Irrespective of what particular initial tarif 5 may be chosen, all that has to be done is to put the stops underneath the respective numbers. The counter wheels are retained in their positions by means of springs 59 resting upon tooth wheels 20.

10 In engagement with tooth wheel 55 (Fig. 1) is a tooth wheel 60 of the trip recorder, and the latter is advanced one number by means of one rotation of shaft 17.

On shaft 61 is further mounted stop disk 15 or cam 62 (Figs. 1 and 4) which admits of only one-third revolution of the wing screw. The latter is restored to its original position by the aid of spring 63. There are moreover fixedly arranged on the shaft cams 64 20 and 65 (see Fig. 5). Cam 65 serves for raising slide 66 (see also Fig. 11) in front of the fare indicator opening. It is intermediated by toothed sector 67 (Fig. 5) which is loosely arranged on shaft 17. Tooth sector 25 67, with its part brought around the counter rollers, engages in lock hook 68 and is held by the same upon the return of cam 65.

Simultaneously with the turning of the wing screw there is also caused the uncoupling between the clock and the fare indicator. This is effected by means of cam 64. On the cam slides lever 71 which is rigidly connected with lever 70 by shaft 69 (Fig. 6). Lever 70 engages under angle lever 72 35 (see Fig. 1) and raises the same. Angle lever 72 likewise engages, upon being lifted, with lock hook 68 (Fig. 5) and is also held thereby on return of cam 64. The clock is thus uncoupled from the recorders by means 40 of coupling 13 (Fig. 1). It is only at start, with the car being occupied by passengers, that lock hook 68 (Fig. 5) by raising of the latter by means of stop lever 73 (Fig. 5) again releases parts 67 and 72.

45 The slide 66 (Fig. 11) is furthermore so arranged that, when uncovering the fare indicator opening, it comes to shut the other four recorder openings.

The engagement and setting of the different tarifs is automatically accomplished 50 upon the passenger sitting down on the spring seat. The seat is in communication with the clock through a Bowden type pull device 75. The number of connections is 55 governed by the number of seats, exclusive of that of the driver.

The connections in the shape of loose pulleys 76 (Fig. 1) engage on rope 79 which is fixedly secured on set bolt 77 in the casing 60 and is guided over rollers or pulleys 78, the said rope being at its other end attached to drum 80 (Figs. 1 and 2). Upon lowering of loose pulleys 76, rope 79 is reeled off from rope drum 80. By rotation of rope drum 80, 65 through action of tooth wheel 81, rack 82

is moved to and fro, and jointly with said rack the wedge bolt 83. Within rope drum 80 is a spiral spring 84 (Fig. 2) the tendency of which spring is to wind rope 79 upon the drum and to shift wedge 5 (Fig. 1) into the transmission wheel of the tarif No. 5. However, since the springs 85 (Fig. 8) of seats 74 possess twice the tractive force of the spiral spring 84 inside the rope drum 80, the consequence is that the loose pulleys 76 75 (Fig. 1) are all pulled downward such that the rope is reeled off from the drum. Incidentally wedge 5 is caused to shift into the notch of transmission wheel 7 mounted fixedly upon the shaft as corresponds to the state of rest. It is only upon the depression of the cushion or seat, or, more precisely speaking, upon removal of the spring force inside the spring seat, that the drum spring 84 (Fig. 2) causes the rope 79 to be wound 85 up a certain length. As a consequence thereof, wedge 5 is shifted into the first transmission wheel 6 and thereby couples the wheel loosely mounted upon the shaft with shaft 4. Upon two or three persons sitting down, 90 the drum spring 84 pulls the corresponding loose pulleys 76 upward while wedge 5 is pushed into transmission wheel 6 corresponding to the tarif involved.

The disengagement of the mileage recorder for trips with passengers is effected 95 through the agency of the stop lever 87 fixedly mounted upon shaft 86 (Figs. 2 and 9) which lever, at the last fifth of the revolution of shaft 86, causes disengaging lever 100 88 engaging in the sleeve of coupling 38 to turn simultaneously. The coupling is engaged by action of spring 89 as soon as stop lever 87 again releases disengaging lever 88 by starting of the clock.

The indication of the number of passengers occurs through circular disk 90 (Fig. 2) which is rigidly arranged on shaft 86, is driven from the rope drum, and is provided with numbers.

Elastic wedges 5 and 9 rest in a slot of wedge bolts 45 and 83 (Fig. 1). The said slot also serves for receiving wedge spring 91. The wedge bolts are shiftably disposed in hollow shafts 4 and 8. The latter likewise are slotted for receiving the wedge. The transmission wheels 6 and 10 are provided each with 3 notches, also for reception of the wedge. Between the transmission wheels are disks without notches, 92, which 115 prevent the wedge from being directly displaced or shifted from one notch of the transmission wheel into the notch of the other wheel. The wedge is first raised out of the notch by disks 92 by application of lateral pressure, and is then allowed to engage in the notch of the next wheel.

The loose pulleys 76 which act upon the rope 79 are held in claws 93 (Fig. 1). The ends of the latter are pivot-shaped and serve 130

to receive stop plate 94. By means of the nuts provided at the block pivots it is feasible to correctly adjust the height. The pivots of the claws have bores for receiving the Bowden rope or cable 75. The latter is directly attached to the spring upholstering by the aid of a special mechanism.

The tarifs can be reduced one-half or be raised twice by means of interchangeable tooth wheel 16 (Figs. 1 and 7) such that any desired tarif can be adjusted to the clock.

Claims:

1. In a taximeter, a rope drum, an indicator disk, a pusher, and means operable by the weight upon a seat for turning said drum through an angle corresponding to the number of seats loaded, and the said pusher moved to actuating position relative to said indicator.

2. A taximeter according to claim 1, wherein means are provided for effecting the change-over from day to night tarif.

3. A taximeter according to claim 1, wherein a wedge bolt, a wedge yieldingly resting in said bolt, a slotted transmission wheel and a rack are provided.

4. A taximeter according to claim 1, with cams connected to the hour wheel, and spring-loaded levers under the influence of said cams for effecting the change-over from day to night tarif.

5. A taximeter according to claim 4, with the said cams adjustable upon their shafts.

6. A taximeter according to claim 1, with an indicator segment, a wedge bolt controlling the same, an angle lever, a rack, a toothed sector and a toothed wheel.

In testimony whereof I affix my signature in the presence of two witnesses.

HERMANN KARL EMIL LÜCKE.
